US0D1101639S

(12) United States Design Patent (10) Patent No.: US D1,101,639 S
(45) Date of Patent: * Nov. 11, 2025

(54) AIR INTAKE GRILLE FOR MOTOR VEHICLE

(71) Applicant: Dr. Ing. h.c. F. Porsche Aktiengesellschaft, Stuttgart (DE)

(72) Inventor: Fabian Schmölz, Stuttgart (DE)

(73) Assignee: Dr. Ing. h.c. F. Porsche Aktiengesellschaft (DE)

() Term: 15 Years

(21) Appl. No.: 29/954,056

(22) Filed: Jul. 25, 2024

Related U.S. Application Data

(62) Division of application No. 29/860,729, filed on Nov. 22, 2022, now Pat. No. Des. 1,057,616.
